TIGHTS

Thomas W. Bradley, Jr., Bristol, Va., assignor to Grey Hosiery Mills, Bristol, Va., a firm

Filed Nov. 12, 1959, Ser. No. 58,310

Term of patent 14 years

(Cl. D3—17)

Fig. 1.

Fig. 2.

The dominant feature of my design resides in the applique ornamentation applied to the tights as shown.

I claim:

The ornamental design for tights, as shown and described.
